UNITED STATES PATENT OFFICE.

ALFRED GARTNER, OF PATERSON, NEW JERSEY, ASSIGNOR TO SCHAUM & UHLINGER, OF PHILADELPHIA, PENNSYLVANIA.

RIBBON-LOOM.

SPECIFICATION forming part of Letters Patent No. 636,979, dated November 14, 1899.

Application filed March 2, 1899. Serial No. 707,505. (No model.)

To all whom it may concern:

Be it known that I, ALFRED GARTNER, a citizen of the United States, residing in Paterson, county of Passaic, and State of New Jersey, 5 have invented certain new and useful Im-

provements in Ribbon-Looms; and I do hereby declare the following to be a full, clear, and exact description of the invention, such as will enable others skilled in the art to which 10 it appertains to make and use the same, reference being had to the accompanying drawings, and to letters of reference marked thereon, which form a part of this specification.

This invention relates to ribbon-looms; and 15 its object is to simplify the construction of said looms by doing away with the heavy batten and the lay-swords supporting the same and by providing a longitudinal reciprocating frame or rail on which the shuttle-blocks, the 20 reeds, and the operating mechanism for the shuttles are mounted. By this arrangement the loom is greatly simplified and rendered more effective and can be operated at a higher speed.

25 The invention consists in the improved ribbon-loom, its horizontally-reciprocating frame or rail carrying the shuttle-blocks, reeds, and the shuttle-operating mechanism.

It further consists in the means for guiding 30 and reciprocating said frame or rail and in the combination and arrangement of the various parts, substantially as will be hereinafter more fully described, and finally embodied in the clauses of the claim.

35 Referring to the accompanying drawings, in which like letters of reference indicate corresponding parts in each of the several views, Figure 1 is a side elevation of a portion of a loom provided with my improvements, 40 the loom-frame being shown in dotted lines, and only such parts of the loom are illustrated which are necessary for a clear understanding of the invention. Fig. 2 is an enlarged transverse sectional view of the reciprocating 45 frame and of the parts mounted thereon, also showing a portion of the guide-rod and of a certain operating-lever. Fig. 3 is an enlarged detail front elevation of a portion of said reciprocating rail or frame (shown in section) 50 and of the shuttle-blocks and intermediate reed mounted thereon; Fig. 4, an enlarged

top plan view of Fig. 1, the loom-frame being shown in full lines with certain portions in section; and Fig. 5, a view similar to Fig. 2, illustrating a slight modification of the reciprocating frame or rail. 55

In said drawings, *a* represents the loom-frame, in which is journaled the main driving-shaft *b* and the take-up roller *c* in the usual and well-known manner. 60

In suitable brackets *d e*, projecting from each of the end sections of the loom-frame *a*, is mounted a guide-rod *f*, at right angles to the main driving-shaft and secured in their respective brackets by means of set-screws *g* 65 or in any desired manner.

It may be well to remark that in the drawings there are shown only two rods *f*, one on each end of the loom, yet a series of intermediate rods may be arranged, if desired, for 70 the purpose of strengthening the construction and mechanism hereinafter described. Upon each rod is slidably mounted a bushing *h*, arranged in a two-part sleeve *i*, downwardly projecting from and one part thereof 75 preferably being integral with the rail *m*, which latter is parallel with the main driving-shaft and is intended to take the place of the ordinary batten.

The rail illustrated in Figs. 1 to 4, inclusive, consists of a flat piece of metal *m'*, provided at its longitudinal edges with downwardly-projecting strengthening-ribs *m² m³*, as clearly illustrated in Figs. 1 and 2. On the top portion of said metallic frame or rail 80 is secured a wooden top plate or raceway *n* by screws *n'* or in any desired manner. On the beveled rear portion of said top plate or raceway are mounted at specified intervals the shuttle-blocks *q*, of the usual and well-known construction, which are adjustably secured to said top plate *n* by means of the clamps *r*, whose bent-over portions *r'* are provided with set-screws *r²*, that engage the top 85 portions of said shuttle-blocks, and whose lower portions are hook-shaped, as at *r²*, and in engagement with the rail or frame *m* and its strengthening-rib, respectively, all as clearly 90 illustrated in Fig. 2.

The pinions *p* are operated in the usual 100 manner by the rack-bar *o*, which in the present case is slidably arranged in the top plate

or raceway *n*, and the reeds *s* are mounted between the shuttle-blocks and upon said top plate or raceway in a manner common to ribbon-looms, the usual strips *u* and *u'* being provided for the purpose of partially sustaining the reeds and of bracing the various clamps *r*.

Adjacent to each sleeve *i* are downwardly-projecting lugs *i*, (preferably integral with the rail *m*,) which are penetrated by a pin or axle *i*², on which is loosely mounted the bushing *i*³, arranged in the forward end of the pitman *i*⁴, the rear portion of which is connected with the main driving-shaft or crank-shaft *b* in the usual manner.

The operation is obvious from the foregoing. When the main driving-shaft is rotating, the pitmen are being operated, and by their connection with the downwardly-projecting lugs of the rail or frame *m* they reciprocate the latter upon the guide-rods *f*, and the reeds accomplish the beating up of the weft in precisely the same manner as in a ribbon-loom in which the batten is being oscillated.

In Fig. 5 I have illustrated a modified form of a rail. Said rail is somewhat narrower than the rail *m* in Fig. 2 and is provided on its front edge with an upwardly-extending flange *m*⁴ and on its longitudinal rear edge with a downwardly-projecting strengthening-rib *m*⁵. On the top of said rail is secured a narrow wooden block *m*⁶, in which is mounted the rack-bar for operating the pinion, and which furnishes a base or support for the shuttle-blocks, as clearly shown. It must be remarked that said wooden block *m*⁶ needs only to be slightly wider than the shuttle-block, as its sole functions are the supporting of said shuttle-blocks and the furnishing of a bearing for the reciprocating rack-bar.

I do not intend to limit myself to the precise construction shown and described, as various alterations can be made without changing the scope of my invention; but

What I claim as new, and desire to secure by Letters Patent, is—

1. In a loom, the combination of a metallic rail adapted to be horizontally reciprocated, a wooden top plate secured upon the top of the same, and provided with a longitudinal groove, a rack-bar arranged in said groove, shuttle-blocks arranged upon said top plate and extending over said rack-bar, pinions journaled in said shuttle-blocks and engag-

ing said rack-bar, and means, engaging the under side of said metallic rail, and the shuttle-blocks for clamping said shuttle-blocks against said top plate, substantially as described.

2. In a loom, the combination of a metallic rail adapted to be horizontally reciprocated and provided with longitudinal and downwardly-extending ribs, a rack-bar arranged in said groove, shuttle-blocks arranged upon said top plate and extending over said rack-bar, pinions journaled in said shuttle-blocks and engaging said rack-bar, and clamps for securing said shuttle-blocks upon the top plate, each clamp having its lower end hook-shaped and engaging a rib of said rail and having its upper end overhanging the top portion of the corresponding shuttle-block and provided with a set-screw engaging the latter, substantially as described.

3. In a loom, the combination of a suitable rail or frame, a rack-bar operatively arranged thereon, shuttle-blocks mounted on said rail or frame, shuttle-driving pinions carried by said rack-bar, and vertical clamps for securing said shuttle-blocks to said rail or frame, each clamp having its lower extremity extending under and adapted to engage the rail or frame and having its upper extremity projecting over and having operative engagement with the corresponding shuttle-block, substantially as described.

4. In a loom, the combination of a suitable rail or frame provided with a longitudinal downwardly-extending rib, a rack-bar operatively arranged thereon, shuttle-blocks mounted on said rail or frame, shuttle-driving pinions carried by said shuttle-blocks and engaging said rack-bar, and vertical clamps for securing said shuttle-blocks to said rail or frame, each clamp having its lower extremity hook-shaped and engaging the rib of said rail or frame and having its upper extremity overhanging the top portion of the corresponding shuttle-block and provided with a set-screw engaging the latter, substantially as described.

In testimony that I claim the foregoing I have hereunto set my hand this 16th day of January, 1899.

ALFRED GARTNER.
